CAR TRUCK

Rudolph Leppla, Davenport, Iowa, assignor, by
mesne assignments, to McConway & Torley
Corporation, Pittsburgh, Pa., a corporation of
Pennsylvania

Application May 23, 1941, Serial No. 394,865

2 Claims. (Cl. 105—197.1)

This invention relates to railway car trucks, and more particularly to an improved spring support for the bolster. In railway freight cars it is necessary that the truck springs have the strength and stiffness to carry the maximum load and that the deflection of the truck springs be so limited that there will not be sufficient difference in the heights of the couplers of a loaded and an empty car to interfere with the action of the couplers. In general freight service the railroads have considerable difficulty by reason of damage to goods carried in lightly loaded cars by reason of the inadequate cushioning action of the heavy cushioning springs.

Differential cushioning spring arrangements are disclosed and claimed in my copending application, Serial No. 381,428, filed March 3, 1941. The present invention is directed to application of the differential cushioning principle to a particular type of truck and to certain improvements.

It is the object of this invention to provide cushioning springs which have a relatively large deflection when subjected to light loads but which have different deflection characteristics when subjected to loads greater than a predetermined amount, and in which the total deflection is not sufficient to cause difficulty in coupling empty cars to heavily loaded cars.

With the above and other objects in view the invention may be said to comprise the truck as illustrated in the accompanying drawing herein-after described and particularly set forth in the appended claims, together with such variations and modifications thereof as will be apparent to one skilled in the art to which the invention pertains.

Reference should be had to the accompanying drawing forming a part of the specification, in which:

Figure 1 is a side elevation of a truck embodying the invention, portions of the side frame, bolster and spring plank being broken away and shown in section;

Fig. 2 is a section taken on the line indicated at 2—2 in Fig. 1, portions of the spring plank and spring cap being broken away to show the structure of underlying parts;

Fig. 3 is a section taken on the line indicated at 3—3 in Fig. 1; and

Fig. 4 is a transverse vertical section showing a modified form of bolster spring.

Since the side frames of the truck and the supports for opposite ends of the bolster are identical, the accompanying drawing shows the con-

struction at one side of the truck only, it being understood that this construction is duplicated at the opposite side of the truck, as is usual in car truck construction.

5 Referring to the accompanying drawing the side frame, indicated generally by the numeral 1, has an upper compression chord 2 and a lower tension chord 3 which connect the end portions of the frame in which journal boxes 4 are pro-

10 vided. The upper and lower chords 2 and 3 are connected intermediate their ends by integral upright columns 5 which are spaced apart to provide a central opening in which a suitable car body supporting member, such as bolster 6, is guided for vertical movement. The bolster 6 and side frames 1 are held against relative tilting movement by suitable means such as guide flanges 7 on the bolster which overlie the inner and outer sides of the columns 5.

15 In the device of the present invention the bolster 6 is supported upon two superimposed sets of cushioning springs, the upper cushioning springs 8 being interposed between the bolster 6 and an intermediate supporting member such as

20 a spring plank 10, and the springs 9 being interposed between the spring plank 10 and the lower chord 3 of the side frame. Various forms of springs may be employed; for example, the springs between the spring plank and bolster

25 may be in the form of a group of coil springs 8, as shown in Figs. 1 to 3, or in the form of an elliptic spring 11, as shown in Fig. 4. When coil springs are employed such as shown in Figs. 1 to 3, suitable spring positioning plates 12 may be provided upon the underside of the bolster and upon the spring plank.

30 The portion of the lower chord extending across the bottom of the side frame opening is preferably of channel form having a bottom web 13 and upwardly extending side flanges 14. The flanges 14 may be extended laterally at their upper edges to stiffen the channel and provide seats 15 for limiting the downward movement of the spring plank 10.

35 A spring cap 16 is supported upon the springs 9 and guided for vertical movement in the side frame. The spring cap 16 supports the end of the spring plank 10 and is preferably rigidly attached to the spring plank by suitable means

40 such as welding. If a cast spring plank is employed, the cap 16 may be cast integrally with the plank. The spring cap 16 is provided with guide portions at the ends thereof which are provided by upwardly extending flanges 17 and depending flanges 18 which provide guide faces of

substantial width and depth which cooperate with the inner faces of the guide columns 5 and which add considerable strength to the cap. The cap 16 is also provided with spaced depending flanges 19 which are disposed at right angles to the flanges 18 and which are disposed within the flanges 14 of the tension chord 3. The end flanges 18 form webs connecting and stiffening flanges 19 at the ends of the spring cap and a similar stiffening web 20 is provided between the intermediate guide flanges 19. The depending flanges 18 and 19 and the cross web 20 provide spring pockets which receive the upper ends of the springs 9. The spring cap 16, with its guide flanges coacting with the columns 5 and tension chord flanges 14, serves to keep the truck square and prevent the side frames from changing their spacing when side thrusts are imposed on the trucks. The upper portions of the side frames being held in position by the bolster and the lower portions thereof being held in position by the spring plank, the side frames are prevented from tilting on the axles. The spring cap 16 is provided with depending flanges 21 along its side edges which, when the cap is seated on the bottom chord, provide additional bracing for the side frames. The springs 9, which are housed within the tension chord channel and the cap 16, may be positioned in the bottom of the channel by suitable lugs or ribs 22 and 23 which may be formed integrally with the web 13.

In order to provide a spring arrangement which will be suitable for light loads as well as heavy loads, it is contemplated that the bolster springs 8 will be of standard design; i. e., they will be stiff enough to adequately cushion and support the maximum load the car is intended to carry. The springs 9, on the other hand, will have more deflection per unit of load than the springs 8 and will be light and flexible enough to adequately cushion a light load. The lighter springs 9, however, are permitted only a relatively small range of movement, the free length of these springs being such that the spring cap 16 will rest upon the seats 15 and the springs 9 will be "stopped off" when a predetermined load is imposed upon the springs. The differential cushioning action due to the stopping off of the weaker spring provides ample deflection for effectively cushioning light loads without an increase in total deflection throughout the range of loads sufficient to interfere with the action of the car couplers.

In order to dampen oscillations, a snubber, such as the snubber 24, may be advantageously employed, preferably in connection with the springs which cushion the heavier loads. The snubber 24, which is shown in connection with the springs 8, is of conventional construction and is therefore not described in detail.

Since under certain conditions of loading the 60

impacts transmitted to the car truck through the truck wheels may cause bumping of the spring plank upon the bottom chord, suitable sound reducing pads 25, which may be formed of rubber and fabric, may be provided on the seats 15.

It is to be understood that variations and modifications of the specific devices herein shown and described for purposes of illustration, may be made without departing from the spirit of the 10 invention.

What I claim is:

1. A car truck comprising side frames having spring supports, lower cushioning springs mounted on the spring supports of each side frame, an intermediate vertically movable supporting member seated upon the cushioning springs of each side frame, upper cushioning springs mounted upon said supporting member, a vertically movable car body supporting member extending 20 across the space between the side frames and seated upon the upper cushioning springs, means for limiting the downward movement of one of said supporting members with respect to the supports for the cushioning springs upon which it is 25 seated to stop off the latter springs, said latter cushioning springs being capable of adequately supporting and cushioning a lightly loaded car body and said limiting means being operable when said latter springs are subjected to the pressure 30 of an excessive load, the other set of cushioning springs being capable of adequately supporting and cushioning a car body having its maximum load and both sets of springs being normally operable, and snubbers interposed between the last 35 mentioned supporting member and the supports for the springs upon which it is seated.

2. A car truck comprising side frames having spring supports, lower cushioning springs mounted on the spring supports of each side frame, an intermediate vertically movable supporting member seated upon the cushioning springs of each side frame, upper cushioning springs mounted upon said supporting member, a vertically movable car body supporting member extending 40 across the space between the side frames and seated upon the upper cushioning springs, the lower cushioning springs being capable of adequately supporting and cushioning a lightly loaded car body and the upper cushioning springs being 45 relatively heavy and capable of adequately supporting and cushioning a car body having its maximum load, said upper and lower springs being normally operable, means for limiting the downward movement of the intermediate supporting member with respect to the side frames when the lower springs are subjected to the pressure of an 50 excessive load, and snubbers interposed between the car body supporting member and the intermediate supporting member.

RUDOLPH LEPPA.
